America as represented by the Secretary of the
Navy

Application March 12, 1946, Serial No. 653,909

13 Claims. (Cl. 317—200)

1

This invention relates to focusing coils for cathode ray tubes or similar devices and more particularly to such coils which are adjustable in position to permit more accurate and better focusing of the electron beam of the cathode ray tube.

In a cathode ray tube, electrons are emitted at the cathode, situated at one end of the tube, and are accelerated by positive potentials in such a manner as to be directed toward the face of the tube at the opposite end. The inner surface of the face, at this opposite end, has been treated with chemical materials to provide a screen which will emit a fluorescent glow when struck by the accelerated electrons. When the electrons are emitted from the cathode, their initial lines of motion are in diverse directions. The fluorescent spots of light which would appear on the face of the tube when these electrons struck it would be widely scattered, or at best, the glow would spread over too large an area for intelligible use if the electrons were allowed to continue in their initial diverse directions. It is therefore necessary to focus the electron stream so that the points of impact with the face of the tube will result in a sharp and well defined spot of light.

The first step in focusing the electron stream, of course, is accomplished by the action of the control grid which causes the electrons to converge first at a point called the crossover point. But this initial point of focus is at a considerable distance from the face of the tube, consequently additional focusing must be introduced to control the stream of electrons as it progresses from the crossover point to the face.

In a magnetic type cathode ray tube, this additional focusing is accomplished by a magnetic field through which the electrons must pass. To procure this magnetic field, a coil of wire, mounted in a toroidal case made of soft iron or equivalent magnetic material, is placed externally around the neck of the tube in such manner that the magnetic field produced by the coil acts upon the electron stream. The coil has the additional function of determining the position of the spot on the face of the tube when the tube is in a static state of operation. Therefore, in order that the focusing and positioning of the spot upon the face of the tube may be accurately controlled, it is necessary that means be provided whereby the coil can be adjusted to any position in a plane perpendicular to the electron stream. Also, since the electron stream is not necessarily parallel with the outer mechanical structure of the tube, additional means must necessarily be pro-

2

vided for angular adjustment of the coil plane with respect to the neck of the cathode ray tube. The position of the coil longitudinally along the neck of the tube is usually fixed in conventional designs and no operational adjustment is provided.

In addition to the above requirements, it is desirable that lateral adjustment does not affect the tilting adjustment or vice versa. It is also desirable that the controls be arranged in such a manner that they are accessible and that they further provide micrometric movement of the coil.

Heretofore, the initial focusing and centering 15 of the image spot on the face of a cathode ray tube has been a difficult and tedious process because of the fact that the tilting or angular adjustment of the focusing coil changed the lateral adjustment and vice versa. This difficulty was 20 due to the fact that no means had been devised to bring the electrical center of the field into alignment with the mechanical center of rotation.

It is an object of this invention to overcome 25 this difficulty.

It is another object of this invention to provide an adjustable focusing coil for magnetic type cathode ray tubes in which the lateral adjustment is electrically independent of the angular adjustment and vice versa.

30 Another object of this invention is to provide an adjustable focusing coil capable of micrometric movement of the coil during the adjustment process.

Another object of this invention is to provide 35 an adjustable focusing coil whose adjustment controls are accessible.

A further object is to provide an adjustable focusing coil which can be adjusted to any position in a plane perpendicular to the electron 40 stream in a cathode ray tube.

A still further object is to provide an adjustable focusing coil which allows the plane of the coil to form an angle with the neck of a cathode ray tube.

These and other objects will become apparent 45 from the following specification when taken with the accompanying drawings in which:

Fig. 1 is a cross-sectional view of the focusing coil in its housing;

Fig. 2 is a top view in partial section of the 50 focusing coil in its housing; and

Fig. 3 is an exploded view of the coil cartridge and its assembly in one embodiment of the invention.

Referring to Fig. 1, the focusing coil 10 is 55 contained in a cartridge comprising housing 11,

core ring 12, gap ring 13, and cap 14. Housing 11, core ring 12, and cap 14 are of magnetic material but the gap ring 13 is of brass or other suitable non-magnetic material. The gap ring is the essence of the operation of a focusing coil since it breaks the continuity of the magnetic path. Because of the gap, some of the flux, generated by a current through the focusing coil, enters the space inside the cathode ray tube through which the electrons pass. It is this portion of the magnetic field, which causes the electrons to be deflected from their straight line motion. If the magnetic field inside the tube is maneuvered correctly, the electrons can be deflected in such manner as to focus at the face of the tube. Ring 15 is a spacer ring of electric insulation to provide clearance for the coil leads and terminals. It also prevents movement of the coil within the case.

In Fig. 2 is disclosed the manner in which the coil leads 16 are soldered at the base of terminals 17 and 18.

By referring to Fig. 3, the assembly of the coil cartridge in the gimbal rings can be explained. The coil cartridge 12 seats in the inner gimbal ring 19. The inside diameter of 19 is reduced in such manner to form a ridge and thus allow the coil cartridge to seat at the proper level, so that the pivot points of the gimbal rings coincide with the electrical center of the magnetic field. A retainer ring 20 fits over coil cartridge 12 and fastens to inner gimbal ring 19. Four screws 20a, 20b, 20c, and 20d fit through holes 21, 22, 23, and 24 of retainer ring 20 and screw into threaded holes 19a, 19b, 19c, and 19d to secure the coil cartridge between retainer ring 20 and inner gimbal ring 19.

Inner gimbal ring 19 fits into outer gimbal ring 25 so that the L-shaped extension 26 lies opposite the inclined ramp 27 and extension 28 is opposite extension 29. Between 28 and 29 is placed a spring 30 which is held in place by a boss on each extension.

Lock screw 31 threads through hole 32 on outer gimbal ring 25 and through hole 33 on inner gimbal ring 19. The tip of 31 presses against coil cartridge 12 at an axial position coinciding with the center of the gap ring 13. Lock screw 34 threads through holes 35 in outer gimbal ring 25 and 36 in inner gimbal ring 19. It presses against coil cartridge 12 at a point also in the center of the gap ring 13. The tips of these two lock screws are directly opposite each other and thus provide the pivot points for inner gimbal ring 19 to pivot with respect to outer gimbal ring 25.

There is an adjusting screw 37 which threads through hole 38 on the L extension 26 and its point operates against the inclined ramp 27 on outer gimbal ring 25. The point is tapered to fit the slope of the ramp and is so located that when the planes of the two rings coincide the point of the screw is midway on the ramp.

The assembly consisting of outer gimbal ring 25, inner gimbal ring 19, coil cartridge 12 and retainer ring 20, now fits into plate 39 in such orientation that L extension 40 is opposite inclined ramp 41 and extension 42 with a boss on it, is opposite boss 43 on plate 39. Spring 44 goes between extension 42 and boss 43. Lock screw 45 threads through hole 46 in ear 47 on plate 39, through hole 48 in outer gimbal ring 25 and its tip terminates in an axial position slightly removed from inner gimbal ring 19. Lock screw 49 threads through hole 50 in ear 51 of plate 39, through hole 52 in outer gimbal ring 25 and its

tip occupies an axial position slightly removed from inner gimbal ring 19 at a point opposite the tip of lock screw 45. The two points allow outer gimbal ring 25 to pivot with respect to plate 39. There is an adjusting screw 53 which threads through hole 54 in L extension 40. Its tip is tapered to follow the slope of inclined ramp 41 on plate 39 and is so located that when the planes of ring 25 and plate 39 coincide, the tip is midway on the ramp. Plate 39 fits on plate 55 in such manner that it is free to move laterally with respect to plate 55, between shoulders 56 and 57. Adjusting screw 58 which controls this lateral movement threads through hole 59 in L extension 60 on plate 55 and has a shoulder which is a running fit in ear 61 of plate 39. Bolt 63 slides through adjusting screw 58 and is held in place by lock nut 64. When bolt 63 is in place, its head fits against the inside face of ear 61.

Plate 55 sits on plate 65 in such manner as to align hole 66 in shoulder 57 with hole 67 in ear 68. Plate 56 is free to move laterally with respect to plate 65 in slides 69 and 70. This lateral movement is controlled by adjusting screw 71, which threads through hole 67. It has a shoulder which is a running fit in hole 66 and is held in place by bolt 72 and lock nut 73 in an arrangement identical to that of adjusting screw 58.

Post 74 seats in hole 75 of clamp dog 76 and the extension of post 74 which is of a reduced diameter fits into hole 77 of plate 65. A tapered pin 78 fits into hole 79 and secures post 74 to plate 65. Clamp screw 80 threads through hole 81 and its tip is tapered to operate against the inclined ramp 82. By tightening clamp screw 80, its tip presses the clamp dog 82 down against plate 39, thereby clamping both plates 39 and 55 against base plate 65 and securing the three plates against vibration or other factors tending to change their relationships. Another clamp dog assembly 83 is secured to base plate 65 through hole 84 in an identical manner to aid in holding the three plates together.

In operation, the neck of a magnetic cathode ray tube fits through hole 85 of the coil cartridge 12. When the tube is operating in its static state, the design of the control circuits should be such that the image spot appearing on the face of the tube is approximately focused and centered. If the spot is in this approximate state, it can be more accurately focused and centered by the adjustment of the control screws, embodied in this invention, in a manner to be discussed below.

The hermetically sealed focusing coil 12, designed as an easily replaceable unit, is carried on two gimbal rings, 19 and 25, which are adjustable by means of two screws, 37 and 53. The coil cartridge is rigidly secured to the inner gimbal ring by retainer ring 20, so that it must move with the inner gimbal ring in any direction which the ring may take.

The inner gimbal ring 19 pivots with respect to outer gimbal ring 25 on an axis determined by the screws 31 and 34. The focusing coil is so positioned that the electrical center of the magnetic gap coincides with the inner gimbal ring pivotal axis. The extension spring 30 tends to keep the inner gimbal ring 19 tilted with respect to the outer gimbal ring 25. The extent of this tilt is determined by the position of the tapered tip of adjusting screw 37. This tip of screw 37 is tapered to fit the slope of the inclined ramp 27 and is so located that when the plane of the two rings coincide, the tip of the screw is midway on the ramp.

The outer gimbal ring 25 is of somewhat similar construction differing only in size and orientation from ring 19. This outer ring pivots with respect to sliding plate 39 on an axis determined by screws 45 and 49. The pivotal axis of gimbal ring 25 is at right angles to that of ring 19 by design. Extension spring 44, tends to keep the outer gimbal ring 25 tilted with respect to the plane of the sliding plate 39. The extent of this tilt is determined by the position of the tapered tip of adjusting screw 53 which is tapered to fit the slope of the inclined ramp 41 and is so located that when the plane of the outer gimbal ring coincides with that of plate 39, the tip of screw 53 is midway on the ramp. Therefore, adjusting screw 53 determines the tilt of the assembled combination of outer gimbal ring 25, inner gimbal ring 19, and focusing coil cartridge 12 with respect to plate 39. Since the two rings are pivoted at right angles to each other, a combination of adjustment of the two tilting screws, 37 and 53, will provide any angular adjustment with respect to plate 39 within limits determined by the length of the inclined ramps 27 and 41.

The gimbal rings, then, provide for any small angular adjustment of the coil with respect to the neck of the cathode ray tube which may be needed to aid in focusing the electron stream.

Sliding plates 39 and 55 with their respective adjusting screws 58 and 71 provide for small amounts of lateral adjustment. Plate 39 rides on plate 55 and is guided in its lateral movement by shoulders 56 and 57. The ear 61 of plate 39 is held between the head of bolt 63 and the shoulder of adjustment screw 58. The tip of screw 58 is a sliding fit in hole 62 of ear 61 but the diameter of the segment of screw 58 containing the threads is larger. This enlarged part of screw 58 provides the shoulder mentioned above. Hence when adjustment screw 58 is screwed inward or outward through threaded hole 59, a lateral movement is imparted to plate 39 and the gimbal ring assembly.

Plate 55 rides on base plate 65 and is guided in its lateral movement by slides 69 and 70. The shoulder 57 of sliding plate 55 is held between the head of bolt 72 and the shoulder of adjusting screw 71 so that when this adjusting screw is rotated clockwise or counterclockwise, plate 55 receives a lateral movement. Plates 39 and 55 move laterally at right angles to each other so that a combination of adjustments of screws 58 and 71 will center the image spot on the face of the tube. These lateral adjustments do not disturb the angular adjustment previously set in.

The four adjusting screws 37, 53, 58 and 71 are positioned radially with respect to the coil for operational convenience and further to permit a deflection coil to be placed adjacent to the focusing coil if required.

The invention described in the foregoing specification need not be limited to the details shown, which are considered to be illustrative of one form the invention may take.

What is claimed is:

1. In combination, a focusing coil for a cathode ray tube or similar device, a pair of gimbal rings, means securing said coil within one of said gimbal rings, a pair of sliding plates, means permitting said pair of gimbal rings to tilt with respect to said pair of sliding plates, means for controlling the amount of said tilt, a fixed plate, means for permitting said sliding plate to move laterally with respect to said fixed plate, and means for controlling the amount of said lateral movement.

2. An adjustable focusing coil comprising, an electromagnetic core, a coil of wire wound thereon, a housing of electromagnetic material for said coil, a gap ring of non-magnetic material to mechanically and electromagnetically separate said core from said housing, a spacer ring to secure said coil in said housing, said coil, core, gap ring, spacer ring and housing being toroidally shaped, terminal posts mounted on said housing, means for connecting said coil to said terminal posts, means for hermetically sealing said coil in said housing, means permitting said coil to tilt in any direction, means for permitting the axis of said tilt to coincide with the mechanical center of said gap ring, a fixed base plate, means for permitting the movement as a unit of said coil and said tilt means in any direction laterally with respect to said fixed base plate without changing the tilt of said coil, and means for permitting micrometric movement of said coil in said directions of tilt and lateral movement.

3. An adjustable focusing coil comprising, an electromagnetic core, a coil of wire wound thereon, a housing of electromagnetic material for said coil, a gap ring of non-magnetic material to mechanically and electromagnetically separate said core from said housing, said coil, core, gap ring, spacer ring and housing being toroidally shaped, terminal posts mounted on said housing, means for connecting said coil to said terminal posts, means for hermetically sealing said coil in said housing, a gimbal ring including means for securing said gimbal ring around said housing, a second gimbal ring including means permitting said first gimbal ring to tilt with respect to said second gimbal ring, a sliding plate including means permitting said second gimbal ring to tilt with respect to said sliding plate, a second sliding plate including means permitting movement of said first sliding plate laterally with respect to said second sliding plate, a base plate including means for permitting movement of said second sliding plate laterally with respect to said base plate, and means for securing said first and second sliding plates to said base plate.

4. An adjustable focusing coil comprising, an electromagnetic core, a coil of wire wound thereon, a housing of electromagnetic material for said coil, a gap ring of non-magnetic material to mechanically and electromagnetically separate said core from said housing, a spacer ring to secure said coil in said housing, said core, coil, gap ring, spacer ring and housing being toroidally shaped, terminal posts mounted on said housing, means for connecting said coil to said terminal posts, means for hermetically sealing said coil in said housing, a gimbal ring into which said coil seats, a retainer ring which fits over said coil housing and bolts to said gimbal ring for securing said coil to said gimbal ring, a second gimbal ring into which said first gimbal ring fits including two lock nut type screws diametrically opposite each other for permitting said first gimbal ring to tilt with respect to said second gimbal ring, an extension spring arrangement tending to tilt said first gimbal ring with respect to said second gimbal ring, an adjusting screw and inclined plane arrangement for controlling the degree of said tilt, a sliding plate into which said second gimbal ring fits including two lock nut type screws diametrically opposite each other and at right angles to said first pair of screws for permitting said second gimbal ring to tilt with respect to said sliding plate, a second extension spring arrangement tending to tilt said second gimbal ring with respect to said sliding

plate, a second adjusting screw and inclined plane arrangement for controlling the degree of said last-mentioned tilt, a second sliding plate against which said first sliding plate fits and with respect to which said first sliding plate is permitted to move laterally including two shoulders for guiding said lateral movement, a third adjusting screw arrangement for controlling the amount of said lateral movement, a base plate into which said second sliding plate fits and with respect to which said second sliding plate is permitted to move laterally including slides for guiding said lateral movement, said slides at right angles to said shoulders of said second sliding plate, a fourth adjusting screw arrangement for controlling the amount of said lateral movement of said second sliding plate with respect to said base plate and two clamp dog-screw arrangements for securing said first and second sliding plates to said base plate.

5. An adjustable focusing coil for an electronic device comprising, an electromagnetic core, a coil of wire wound thereon, a housing for said coil, a ring of non-magnetic material for separating said core from said housing, means for tilting said coil in any direction relative to the axis of said device, means independent from said tilting means for moving as a unit said coil and said tilting means in any direction laterally relative to said device without changing the tilt of said coil, and micrometric means for fine adjustment of any of the movements of said coil.

6. An adjustable focusing coil for an electronic device comprising, an electromagnetic core, a coil of wire wound on said core, a housing for said coil, a ring of non-magnetic material separating said core from said housing, said ring being disposed about said core and positioned for breaking the continuity of the magnetic path associated with said coil, means for tilting said coil in any direction relative to said device and means independent from said tilting means for moving as a unit said coil and said tilting means in any direction laterally relative to said device, said any tilt direction remaining the same independently of the operation of said lateral moving means.

7. An adjustable focusing coil comprising, an electromagnetic core, a coil of wire wound on said core, an electromagnetic housing for said coil, a ring of non-magnetic material separating said core from said housing, a fixed base plate, means for tilting said coil in any direction relative to said base plate, means operable independently of said tilting means for moving as a unit said coil and said tilting means in any direction laterally with respect to said base plate without changing the tilt of said coil, and micrometer screw devices for adjusting the position of said coil in any desired direction.

8. In combination, a focusing coil for an electromagnetic device, a housing for said coil, a gimbal ring including means for securing said gimbal ring around said housing, a second gimbal ring including means permitting said first gimbal ring to tilt with respect to said second gimbal ring, a first sliding plate including means permitting said second gimbal ring to tilt with respect to said sliding plate, a second sliding plate including means permitting movement of said first sliding plate laterally with respect to said second plate, a base plate including means for permitting movement of said second sliding plate laterally with respect to said base plate, and means for securing said first and second sliding plates to said base plate.

9. In combination, a focusing coil for an electromagnetic device, means for tilting said coil in any direction relative to the axis of said device, and means independent from said tilting means for moving said coil and said tilting means as a unit in any direction laterally relative to said device without changing the tilt of said coil.

10. In combination, a focusing coil for an electromagnetic device, a base plate fixed with respect to said device, means for tilting said coil in any direction relative to said base plate, means operable independently of said tilting means for moving said coil and said tilting means as a unit in any direction laterally with respect to said base plate and said device without altering the tilt of said coil as determined by said tilting means.

11. In combination, a focusing coil for a cathode ray tube or similar device, first and second cooperating gimbal rings, means securing said coil within said first gimbal ring, first and second sliding plates, means supporting said second gimbal ring on said first sliding plate and arranged to permit said first and second gimbal rings to tilt with respect to said sliding plates, a third plate fixed in position with respect to said cathode ray tube, means secured to said third plate and arranged to permit lateral movement of said second plate thereon in one direction, and means secured to said second plate and arranged to permit lateral movement of said first plate thereon in a direction transverse to said one direction.

12. An adjustable focusing coil for a cathode ray tube, or the like, comprising in combination with said coil, a base plate fixed in position relative to said tube, a first plate slidably mounted on said base plate for movement in one direction relative to said base plate, a second plate slidably mounted on said first plate for movement relative thereto in a direction transverse to said one direction, a first gimbal ring pivotally mounted on said second plate, a second gimbal ring pivotally mounted within said first gimbal ring, and means securing said coil within said second gimbal ring.

13. An adjustable focusing coil for a cathode ray tube, or the like, comprising, in combination with said coil, a base plate fixed in position with respect to said tube, a first plate slidably mounted on said base plate for movement in one direction, a second plate slidably mounted on said first plate for movement relative thereto in a direction transverse to said one direction, and means surrounding said coil and pivotally mounted on said second plate for tilting said coil in any direction relative to the axis of said tube.
